UNITED STATES PATENT OFFICE.

FRANK S. RECE, OF DALLAS, TEXAS.

CRIB HOOK.

Application filed April 30, 1926. Serial No. 105,689.

This invention relates to new and useful improvements in crib hooks.

The invention has particularly to do with hooks for attaching a roller-mounted crib 5 to the side of a bed.

The object of the invention is to provide a hook of the type shown in my co-pending application, Serial No. 704,814, and to arrange it so that it will catch or engage the 10 bottom instead of the top of the rail, thus not interfering with the mattress of the bed, which usually overhangs said rail.

Another object of the invention is to provide a vertically adjustable hook with means 15 for automatically holding it at the elevation to which it is adjusted, whereby said hook is made self sustaining.

A construction designed to carry out the invention will be hereinafter described together with other features of the invention. 20

The invention will be more readily understood from a reading of the following specification and by reference to the accompanying drawings, in which an example of the 25 invention is shown and wherein:

Fig. 1 is a transverse vertical sectional view of adjacent portions of a crib and bed held in contiguous relation by a hook constructed in accordance with my invention,

30 Fig. 2 is an enlarged vertical sectional view of the hook taken on the line 2—2 of Fig. 3,

Fig. 3 is an enlarged horizontal cross-sectional view taken on the line 3—3 of 35 Fig. 1,

Fig. 4 is an elevation of another form of the hook,

Fig. 5 is a cross-sectional view taken on the line 5—5 of Fig. 4,

40 Fig. 6 is a cross-sectional view of still another form,

Fig. 7 is a cross-sectional view taken on the line 7—7 of Fig. 6, and

Fig. 8 is a cross-sectional view taken on 45 the line 8—8 of Fig. 4.

In the drawings the numeral 10 designates a baby crib mounted on wheels, only one of which 11, is shown. The crib has a mattress 12 suitably supported on a level with the 50 mattress 13 of a bed 14. By means of my invention the mattresses are held in contact and the mother may roll or slide the baby from one to the other, without the exertion of lifting.

55 The crib being mounted on wheels must be held contiguous to the bed or else, it

would be pushed away and leave a gap between the mattresses. As the ordinary crib is shorter than the average bed, the side rail 15, becomes the logical element to which to 60 attach the crib.

For this purpose I provide at each end of the crib a hook comprising a U-shaped bill 16, bent parallel to a depending shank 17 having a head 18 at its lower end. This 65 hook may be formed of heavy gauge wire, as for instance #10, or it may be otherwise made, as the manufacturer requires. The bill may be covered with a piece of rubber tubing 19 or otherwise sheathed to prevent 70 injury to the side rail.

The hook is mounted in a carrier 20 which is formed of a flat plate slidable in a vertical channel bar 21 having ears 22 at each end by which it is secured to the corner post 75 23 of the crib by means of screws 26. The carrier has outwardly directed ears 24 at its upper and lower ends and the shank 17 is pivoted therein. The hook is supported by the upper ear 24 and the head 18, below 80 the lower ear 24, limits the upward displacement of said hook.

The carrier plate 20 has a thickness less than the depth of the channel, as is shown in Figs. 2 and 3, and this provides space for 85 a flat friction spring leaf 25 bowed between its ends and interposed between the back of the plate and the bottom of the channel. The ends of the spring leaf are bent over the upper and lower ends of the plate, 90 or said spring leaf may be otherwise secured. The spring leaf forces the sides of the plate into contact with the lips of the channel bar 21 and thus frictionally holds the carrier at the elevation to which 95 it is slid. The heads of the screws 26 which fasten the ears 22 prevent displacement of the carrier from the channel bar.

The hook is freely rotatable in the carrier and when not in use, the carrier may be slid 100 down the channel bar and the bill 16 engaged in a keeper 27 mounted on the inner side of said bar. This prevents the hook from catching on things or swinging loosely when the crib is moved about.

105 It is obvious that the hook may be mounted in various forms of carriers and the invention is not to be limited to the particular forms shown herein. In Figs. 4 to 7 I have shown other forms as examples.

110 In Figs. 4 and 5 a carrier 30 in the form of a link or loop is shewn. This link has an

enlarged vertical opening or slot 31 through which a flat supporting bar 32 passes. This bar has inwardly offset ears 33 at each end secured to the post 23 whereby the bar is spaced from the post and the link may be freely slid. The said link has a leaf spring 34 bent upon itself and one end secured to the link within the slot, while the free end of the leaf rests against the face of the bar 32. The shank 17 of the hook is hinged in a vertical aperture 35 extending through the link at one side of the slot. The frictional contact of the spring holds the carrier at the elevation to which it is adjusted. In Figs. 6 and 7 I have shown a carrier 40 composed of soft rubber or other suitable material and having an opening 41 extending therethrough snugly receiving a supporting bar 42 having offset ears 43 at its ends. The bar may be made of a stout wire or small round rod and the carrier made to fit sufficiently tight thereon to frictionally embrace the bar and thus remain at elevated adjustments. The shank 17 of the hook is hinged in the carrier at one side and the offset weight of the hook will tend to "cant" the carrier on the bar, thus holding it against sliding down on the bar unless manually moved.

When it is desired to attach the crib to a bed the crib is moved to the side of the bed and its mattress 12 adjusted to the mattress 13 of the bed. The hooks are individually lifted from their keepers 27 and swung under the side rail 15 of the bed. Each hook is then adjusted by sliding the carrier 20 upwardly in its channel bar 21 so that the bill 16 and its tube 19 are engaged under the said rail 15, as is shown in Fig. 1. The friction spring leaf 25 of each carrier will hold the hook in engagement with the bed.

With the crib attached in this simple manner, it cannot roll away from the bed and the mattresses may be abutted. When the person occupying the crib-side of the bed desires to rise from the bed it is merely

necessary to discharge the hook nearest the foot of the bed, the hook at the head becoming a pivot, whereby the crib may be swung away from the bed and returned after the person has stepped from the bed. The hook carriers are easily and quickly manipulated and the supporting bars are long enough to permit the adjustment of the hooks to bed rails at various heights.

Various changes in the size and shape of the different parts, as well as modifications and alterations, may be made within the scope of the appended claims.

What I claim is:

1. A device for attaching a crib to a bed comprising, an upright support for stationary mounting on a crib, a carrier movable on the support and having frictional contact therewith whereby it is sustained at adjusted elevations, a hook hinged to the carrier and having an upturned bill for engaging beneath the side rail of a bed, and a keeper having vertical and horizontal engaging faces for supporting the hook against swinging or downward movement.

2. A device for attaching a crib to a bed comprising, a vertical channel bar, a carrier slideable in the channel bar, a spring element interposed between the carrier and the bar and mounted on the carrier, and hook hinged on the carrier and free to swing, said hook having an up-turned bill for engaging under the side rail of a bed.

3. A device for attaching a crib to a bed comprising a vertical guide bar, a carrier slideable upon said bar, means for holding the carrier against rotation upon the bar, a friction element interposed between the carrier and the bar and mounted upon the carrier, and a hook having means by which it is hinged upon the carrier and free to swing horizontally, said hook having an up-turned bill for engaging under the side rail of a bed.

In testimony whereof I affix my signature.

FRANK S. RECE.
